UNITED STATES PATENT OFFICE

2,666,381

MACHINE FOR APPLYING STRAPS TO
CONTAINERSVernon C. Sherman, Plymouth, and Bradford H.
Cole, Carver, Mass.

Application November 29, 1949, Serial No. 130,032

3 Claims. (Cl. 100—31)

1

Our invention relates to machines for applying straps to containers. As is well known, many containers are either reinforced and/or have a cover secured thereto by wrapping a metal strap or straps about the container, tensioning overlapped ends of the strap and securing said overlapped ends together while under tension. Machines for tensioning and securing straps to containers are well known and of a wide variety. Normally, such machines are positioned on top of the container, a strap is manually wrapped about the container with the free ends thereof threaded through the machine in overlapping relation for engagement by gripping fingers in the machine. Thereafter, the machine is actuated to tension and/or to secure the overlapped ends of the strap together. In carrying this out, the gripping fingers or fingers of the machine are disposed below the tensioned and secured strap whereby considerable effort must be applied to withdraw the fingers from beneath the tensioned strap. Also, such strapping machines are relatively heavy, whereby the effort of moving them about from container to container is considerable. Also, where the straps must be applied to rabbeted grooves formed in a container, it is relatively difficult to locate the machine manually in the proper position for securing a strap in the rabbeted groove.

With the foregoing in view, it is an object of our invention to provide novel adjustable supports for a strapping machine and for a container to be strapped, and wherein at least one of the supports is adjustable relative to the other whereby to accommodate containers of varying size.

A further object is to provide in a device such as that last described means mounting one of said supports for movement relative to the other into and out of an operative position wherein the strapping machine is operatively positioned or moved away from a container to be strapped.

A further object is to provide an improved mount for a strapping machine, means for moving the mount into and out of operative position relative to a container to be strapped, and means for moving the mounting machine relative to its mount so as to disengage the machine from a tensioned and secured strap.

A further object is to provide an improved support for a container to be strapped, wherein said support includes guide means adjustable relative to each other for operatively positioning containers of various sizes on the support relative to a strapping machine support.

2

Other objects and advantages reside in the particular structure of the invention, the structure of the several elements forming the same, combinations and sub-combinations of such elements, all of which will be readily apparent to those skilled in the art upon reference to the attached drawings in connection with the following specification, wherein the invention is shown, described and claimed.

In the drawings:

Figure 1 is an elevational view of the machine according to the invention, showing the same in use, the strapping machine being shown diagrammatically;

Figure 2 is an end elevation of the machine taken on the line 2—2 of Figure 1, the strapping machine being omitted;

Figure 3 is a fragmentary top plan view of the machine of Figures 1 and 2, the strapping machine being shown diagrammatically;

Figure 4 is an enlarged front end elevational detail view of the strapping machine employed on the apparatus of Figures 1 to 3, said strapping machine being shown ready for removal from engagement with a strap which has just been fastened around a container;

Figure 5 is an enlarged cross-sectional detail view taken in line 5—5 of Figure 3;

Figure 6 is a top plan detail view of the adjustable container supporting table employed in the apparatus of Figures 1 to 3;

Figure 7 is a cross-sectional detail view taken on line 7—7 of Figure 4.

Referring specifically to the drawings, wherein like reference characters have been used throughout the several views to designate like parts, 10 designates generally and diagrammatically any well known form of portable strapping machine. At this time, it should be noted that the machine 10 by itself forms no part of our invention, as it is an important feature of our invention that it is usable with any of a wide variety of strapping machines solely by modifying them to provide means for attaching them to the strapping machine mount. Suffice it to say that the machine 10 is capable of gripping and tensioning a metal strap 13 so as to secure the overlapped ends of the strap together by any suitable clip, such as shown at 11. In the embodiment illustrated in Figures 1, 4 and 7, the strap 13 is secured in the rabbets 15 formed adjacent the ends of any suitable container, such as a beverage box 14. Moreover, it is to be understood that the machine 10 includes one or more gripping and/or tensioning fingers which normally are clamped between the

tensioned and secured strap ends and the container 14. Likewise, it is understood that such finger or fingers may be disengaged from such clamped position by movement of the machine from right to left, as viewed in Figure 1. With the foregoing in view, the apparatus comprising the invention will now be described.

Thus, our device comprises a base 16 which is suitably secured to a floor or support. The base or bed 16 has fixed thereto a pair of laterally spaced and substantially vertically extending standards 18 and 19. The standard 18 is adjacent the forward end of the base or bed 16 and adjacent the upper end of such standard and connected to the standard 18 for vertical movement is a horizontally disposed table 25. The standard comprises a lower section 20 fixedly secured to the base and an upper section 21 telescopically connected to the lower section 20 for vertical adjusting movement relative thereto and to the base 16. In the embodiment illustrated, the lower section 20 comprises a tubular post slidably and telescopically receiving the lower end of the upper section 21. Any suitable means for vertically adjusting and maintaining the upper section 21 in a vertically adjusted position relative to the lower section 20 may be provided.

In the embodiment illustrated, the member 21 is formed with rack teeth 122 and the member 20 carries a bracket 123 in which is journaled a horizontal shaft 124 carrying rack gears 125 engaging the rack teeth 122. Secured to one end of shaft 124 is a disc 126 provided with a crank handle 127. Rotation of disc 126 by means of handle 127 elevates or lowers the member 122 with respect to member 20. Diametrically opposite the rack gears 125 the bracket 123 carries a radial set screw member 23 threaded through the bracket and the member 20 and being lockingly engageable with the member 21. Thus, with the set screw 23 in unlocking position the member 21 may be raised or lowered to a desired position of vertical adjustment, and by tightening the set screw the member 21 may be locked in said desired position. Obviously, other means for maintaining the sections in adjusted relation may be provided. The upper end of the upper section 21 has fixedly secured thereto atop the same the table 25. The table 25 has a flat upper surface adapted to slidably receive thereon the container 14. To accommodate containers of varying sizes, the table 25 is not only vertically adjustable, as aforesaid, with the upper section 21, but is also provided with left and right-hand side guides for the container, as indicated at 26 and 27, Figure 2. The side guides are mounted for movement toward and away from each other atop the table 25 by any suitable means, such as the rods 28 which are slidably in the sleeve bearings 29 fixed to the table top. Thumb screws 30 are carried by the sleeves 29 and are disposed therethrough for frictional engagement with the rods 28 to lock the guides 26 and 27 in adjusted positions. In the embodiment illustrated, the guides 26 and 27 comprise angle bar members including vertical webs 26' providing side guides and horizontal webs 27' slidably on the table top and supporting the container 14 thereon between the vertical webs or flanges. To limit rearward movement of the container 14 along the horizontal flanges of the side guides 26 and 27, an end stop 31 has been provided which comprises the laterally inwardly directed free end of a plate 32 slidable along side the vertical flange of the side guide 27. The

plate 32 includes a downwardly directed hook 33 riding on the vertical flange 26' of the side guide 27 and having a thumb screw 34 threaded therein for engagement with the outside of the vertical flange of the side guide 27 whereby to adjustably secure the end stop 31 to the side guide 27. If desired, a similar end stop may be provided for the side guide 26.

Referring now to the rear standard 29, it is noted that the same is substantially taller than the forward standard 18. A horizontally disposed support 40 for a strapping machine is arranged in superimposed spaced relation with respect to the table 25 and is connected at one end to the standard 19 for vertical movement relative to the table 25 and for rotational movement about the standard 19 as an axis. An adjustable split collar 36 is slidably mounted on the standard 19 and is secured thereon by clamping screw 37. The collar 36 preferably has secured thereto a radially directed arm 38 providing a stop for the strapping machine support, now to be described.

The strapping machine support is generally indicated at 40 and comprises a hub assembly 41 which is slidably and rotatably journaled on the upper portion of the standard 19. The hub assembly 41 is maintained at an adjusted height by being supported on the collar 36 aforesaid. A support arm 42 is fixedly secured to the assembly 41 in any suitable manner, as by being welded thereto, and is braced by an upwardly directed strut 43 having its upper end fixed to a collar 44 slidably and pivotally journaled on the standard 19 above the assembly 41. The hub assembly 41 has a depending stop 45 fixed thereto adapted to engage the stop 38, whereby to limit pivotal movement of the arm 42 in one direction. As will appear later, the stops 45 and 38 are so disposed that when engaged the strapping machine 10 is correctly positioned relative to a container 14 supported on the table 25.

The support arm comprises a pair of laterally spaced arm members upon one of which is mounted a slide 46 which is adapted to be positioned in adjusted relation to a container 14 by means of a thumb screw 47. The slide 46 includes a downwardly directed end stop 48 adapted to cooperate with the end stop 31 to limit movement of the container 14 in one direction. A carriage 50 extends longitudinally of the support 40 and has one end adjacent to and spaced from the other end of the support 40, the carriage being connected intermediate its ends to the support 40 for longitudinal, extensible and contractile movement with respect to the other end of the support. Specifically, the free ends of the arm members of the arm 42 of the support 40 are connected together by means of a crossbar 42, the space between the arm members of the arm 42 inwardly of the crossbar 42 forming a longitudinally extending slideway 49, Figure 3, in which is longitudinally slidable a carriage 50 comprising a mount for the strapping machine 10. Thus, the free end of the carriage 50 has secured thereto an angle member 51 which has a downwardly directed end flange 52 through which screws (not shown) extend for securing the strapping machine 10 to the carriage 50.

To actuate the strapping machine carriage 50 longitudinally of the arm 42, a plate 53 is operatively secured atop the carriage and has an intermediate portion formed with rack teeth 54. The teeth 54 are in constant mesh with a pinion 55 fixed to a rock shaft 56 which in turn is jour-

naled in a pair of laterally spaced bearings 57 fixedly secured to the arms of the support 42. A rock lever 58 is fixed to the shaft 56 laterally of the support 42. As is obvious from the foregoing, rocking of the shaft 56 in opposite directions will cause the pinion 55 to drive the rack 54 and the strapping machine carriage 50 longitudinally of the arm 42 in opposite directions. Normally, the strapping machine carriage 50 is positioned on its most forwardly extended position by means of a spring 59, of an expansive nature, which is interposed between a pair of upstanding abutments 60 and 61, the abutment 60 being fixed to the arm 42, while the abutment 61 is located on the rear end of the carriage 50.

To actuate the carriage 50 in the opposite or rearward direction, a push rod 62 is provided, the push rod including a T-shaped upper yoke 63 provided with a roller 63' adapted to engage the rock lever 58 upon upward movement of the push rod 62. The upper end of the push rod 62 is guided in a fixed guide 64 extending upwardly of and rigidly secured to the base 16. The push rod 62, yoke 63 carrying the roller 63', and fixed guide 64 projecting upwardly and supported upon the base 16, constitute an operating mechanism 25 guidingly mounted in relation to the first standard or standard 18 for manually actuating the means operatively connected to the carriage 50, the latter means embodying the plate 53 carrying the rack teeth 54 in mesh with the pinion 55 carried by the rock shaft 56 which has a rock lever 58 engageable with the roller 63' of the push rod 62. The lower end of the push rod 62 is pivotally connected by any suitable pivot 65' to the rear end of a pedal 65 pivoted to the base 16 intermediate its ends by any suitable pivot 67. It is obvious that when the pedal 65 is depressed, the push rod 62 will be elevated, whereby to rock the rock shaft 56 in a clockwise direction, as viewed in Figure 1, whereby the pinion 55 moves the rack 54 together with the attached strapping machine mount 50 from right to left so as to withdraw the strapping or clamping fingers, not shown, of the machine from beneath the strap 13. Thus, the strapping machine 10 is quickly freed from the strap 13 after the same has been tensioned and secured.

In operation, with the table 25 and other adjustable parts preset for containers 14 of a selected size, the support 42 may be swung to the left to an inoperative position, as viewed in Figure 2. After a container 14 is seated against the stops on the table 25, the support 42 is swung back to the position indicated in Figure 1, at 50 which point the machine 10 is properly positioned over the top of the container 14. A strap 13 is now threaded about the container and through the machine 10. The handles 70 and 71 of the machine 10 are now actuated to tension and secure the strap 13 about the container 14. As aforesaid, this operation places the actuating fingers of the machine above and adjacent to the container 14, as shown in Figure 4. Thereafter, the operator steps on the pedal 65, whereby 55 the carriage for the machine and the machine are moved from right to left, Figure 1, to free the machine from the secured strap 13. Thereafter, the support 42 is swung to the left from the position indicated in Figure 2, clear of the table 25. The container 14 may now be reversed, if desired, and a second strap 13 secured to the opposite end, by a repetition of the foregoing operation.

Referring to Figure 7, it will be seen that the 75

strap 13 may be of a type formed with spaced downwardly facing marginal corrugations, whereby the clamping tension on the strap causes the downwardly directed edges of the strap to penetrate into the surface of the rabbed seat 15, thereby greatly increasing its holding effect and insuring proper placement of the strap in said seat prior to nailing.

Obviously, this arrangement results in efficient and uniform strapping of containers, requires no manual lifting or moving of the machine 10 except to swing the same into and out of position. Moreover, it is apparent that the device is readily adaptable to a wide variety of differently sized containers 14. Moreover, while we have shown and described what is now thought to be a preferred embodiment of the invention, it is to be understood that the same is susceptible of other forms and expressions. Consequently, we do not limit ourselves to the precise structure shown and described hereinabove except as hereinafter claimed.

We claim.

1. A machine for applying straps to containers comprising a first standard, a horizontally disposed table disposed adjacent the upper end of said standard and connected to said standard for vertical movement for supporting a container to which straps are to be applied, means operatively connected to said standard for holding said table in a select position of its vertical movement, a second standard arranged in spaced relation with respect to said first standard, a horizontally disposed support arranged in superimposed spaced relation with respect to said table and connected at one end to said second standard for vertical movement relative to said table and for rotational movement about said second standard as an axis, a carriage extending longitudinally of said support and having one end adjacent to and spaced from the other end of said support, said carriage being connected intermediate its ends to said support for longitudinal extensible and contractile movement with respect to the other end of said support, means on said one end of said carriage for attachment of a strapping machine thereto, means operatively connected to said carriage for effecting the extensible and contractile movement of the latter, and operating mechanism guidingly mounted in relation to said first standard for manually actuating the means operatively connected to said carriage.

2. A machine for applying straps to containers comprising a first standard, a horizontally disposed table disposed adjacent the upper end of said standard and connected to said standard for vertical movement for supporting a container to which straps are to be applied, means operatively connected to said standard for holding said table in a select position of its vertical movement, a second standard arranged in spaced relation with respect to said first standard, a horizontally disposed support arranged in superimposed spaced relation with respect to said table and connected at one end to said second standard for vertical movement relative to said table and for rotational movement about said second standard as an axis, a carriage extending longitudinally of said support and having one end adjacent to and spaced from the other end of said support, said carriage being connected intermediate its ends to said support for longitudinal extensible and contractile movement with respect to the other end of said support, means on said one end of said

carriage for attachment of a strapping machine thereto, means operatively connected to said carriage for effecting the extensible and contractile movement of the latter; operating mechanism guidingly mounted in relation to said first standard for manually actuating the means operatively connected to said carriage, and spring means operatively connected to said support and to said carriage adjacent the other end of the latter for biasing said carriage toward its extensible movement position.

3. A machine for applying straps to containers comprising a first standard, a horizontally disposed table disposed adjacent the upper end of said standard and connected to said standard for vertical movement for supporting a container to which straps are to be applied, means operatively connected to said standard for holding said table in a select position of its vertical movement, a second standard arranged in spaced relation with respect to said first standard, a horizontally disposed support arranged in superimposed spaced relation with respect to said table and connected at one end to said second standard for vertical movement relative to said table and for rotational movement about said second standard as an axis, a carriage extending longitudinally of said support and having one end adjacent to and spaced from the other end of said support, said carriage being connected in intermediate its ends to said support for longitudinal extensible and contractile movement with respect to the other end of said support, means on said one end of said carriage for attachment

of a strapping machine thereto, means operatively connected to said carriage for effecting the extensible and contractile movement of the latter; operating mechanism guidingly mounted in relation to said first standard for manually actuating the means operatively connected to said carriage, spring means operatively connected to said support and to said carriage adjacent the other end of the latter for biasing said carriage toward its extensible movement position, and a foot actuatable means operatively connected to said operating mechanism for effecting the contractile movement of said carriage.
